US0D1001754S

(12) **United States Design Patent** (10) **Patent No.:** **US D1,001,754 S**
Ann et al. (45) **Date of Patent:** ** Oct. 17, 2023

(54) **MONITOR**

- (71) Applicant: **Samsung Electronics Co., Ltd.**, Gyeonggi (KR)
- (72) Inventors: **Sungjin Ann**, Gyeonggi (KR); **Taeyeon Won**, Gyeonggi (KR); **Wonchul Hwang**, Gyeonggi (KR)
- (73) Assignee: **SAMSUNG ELECTRONICS CO., LTD.**, Gyeonggi (KR)

(**) Term: **15 Years**

(21) Appl. No.: **29/695,314**

(22) Filed: **Jun. 18, 2019**

(30) **Foreign Application Priority Data**

Dec. 24, 2018 (KR) 30-2018-0061320

(51) **LOC (14) Cl.** **14-02**

(52) **U.S. Cl.** **D14/336**; D14/126
USPC .....

(57) **CLAIM**

The ornamental design for a MONITOR, as shown and described.

DESCRIPTION

FIG. 1 is a front perspective view of a Monitor, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and

FIG. 9 is another rear perspective view of the Monitor shown in an alternate position.

The even-dash broken lines illustrating portions of the Monitor form no part of the claimed design. The dot-dash broken lines defining the boundary of the claimed design form no part of the claimed design

1 Claim, 9 Drawing Sheets
